UNITED STATES PATENT OFFICE

ALDEN A. POTTER, OF MONTGOMERY COUNTY, MARYLAND

CASEMENT

Application filed September 26, 1927. Serial No. 221,953.

My invention consists in a new and useful improvement in casements and is designed to provide a casement suitable for a window where only a single sash is to be used. The particularly novel and useful feature of my device is the means which I provide to permit the casement to be pivoted on its lower edge so that it may be partly opened at the top, and also permit it to be pivoted at its upper edge so that it may be fully opened. In my device, I have provided a swinging casement which may also be slid relative to its frame, a novel feature in these devices.

While I have illustrated in the drawings filed herewith, and have herein fully described one specific embodiment of my invention, it is to be distinctly understood that I contemplate many other embodiments, do not consider the invention limited to the specific embodiment herein illustrated and described, but refer for the scope of my invention to the claims appended hereto.

In the drawings:

Fig. 1 is front elevation of the casement, parts shown in normal position.

Fig. 2 is a similar view, parts shown in adjusted position.

Fig. 3 is a vertical section, the casement being shown in full lines in one open position, and shown in dotted lines in closed position shown in Fig. 1.

Fig. 4 is a vertical section, the casement being shown in full lines in another open position, and shown in dotted lines in closed position shown in Fig. 2.

Fig. 5 is an enlarged vertical section, on line 5—5 of Fig. 6.

Fig. 6 is an enlarged horizontal section, on line 6—6 of Fig. 1.

In the specific embodiment of my invention illustrated in the drawings, I have shown a frame F for the casement, having a sill 1, a stool 2, a top apron 3, and side stops 4. The casement C is received in the frame F and normally rests upon the sill 1, outside of the stool 2 and inside of the apron 3 and side stops 4, as shown in Fig. 1, and in dotted lines in Fig. 3. The side members 5 of the casement C are provided

at their upper parts with rabbeted portions 6 in which are received, when the casement C is in normal position, slotted arms 7 carried by bolts 8 in the upper part of the frame F adjacent the apron 3. Pins 9 in the side members 5 serve to effect a slot-and-pin connection between the casement C and the frame F, through the arms 7 pivoted on the bolts 8. Adjacent the bottom of the rabbeted portions 6, each side member 5 is provided with a mortised bolt 10 having a rack 11 with which meshes a pinion 12 on a mortised shaft 13 having an operating knob 14 projecting from the inner face of the side member 5. The frame F is provided with suitably disposed sockets 15 for receiving the ends of the bolts 10. The bolts 10 and sockets 15 may be complementarily obliquely faced, so that when the bolts 10 are received into the sockets 15 they serve to clamp the casement C against the apron 3 and side stops 4 in the frame F. It is to be noted that the slotted arms 7, bolts 10 and sockets 15 are so disposed in relation to one another that when the casement C is in normal position, as shown in Fig. 1, the bolts 10 register with the sockets 15, and may be received therein, and that when the casement C is slightly raised so as to clear the stool 2, as indicated in Fig. 2, the bolts 10 register with the lower extremities of the slots in the arms 7 and may be received therein. At the upper edge of each rabbeted portion 6 in the side members 5 of the casement C, I provide a semi-circular recess 16 into which is received the head of the bolt 8, when the casement C is raised, as shown in Fig. 2. I have also illustrated (though no part of my invention) a netted screen 17 applied to the outside of the frame F, to indicate that the opening may be covered by a permanently attached outer screen, with which there will be no interference by the manipulation of my improved casement.

From the foregoing description of the details of construction of my device, its operation and use will be obvious. When the parts are in normal position, as shown in

Fig. 1, the bolts 10 may be retracted by turning knobs 14, and the casement C, being released from the frame F, may be swung inwardly, pivoting on its lower edge resting on the sill 1. The pins 9 slide in the slotted arms 7 until the ends of the slots are reached, and the arms 7 limit the movement of the casement C, so that it assumes the position shown in full lines in Fig. 3. When the casement C is in this position, it will be seen that ventilation is afforded through the opening at the top of the casement C, without exposing the interior to the weather. It is also to be noted that the casement C can be adjusted for ventilation without disturbing the screen 17.

If it is desired to fully open the casement C, the parts may be adjusted as shown in Fig. 2, the casement C being slid upwardly in the frame F sufficiently to clear the stool 2. The bolts 10 are projected to engage the lower ends of the arms 7 through the slots thereof. The casement C is thus supported by the arms 7 which serve, with the bolts 8, as hinges for the casement C. It may then be swung inwardly and upwardly, pivoting at its upper edge, to the position shown in full lines in Fig. 4, being retained in such position by any suitable fastening means.

Having described my invention, what I claim is:

1. The combination with a frame therefor of a casement; means adapted to limit the movement of the casement when it is pivoted on its lower edge; and reciprocable means adapted to co-act with said limiting means to furnish a hinge for said casement at its upper edge.

2. In a casement fixture, the combination of a pivoted member; a permanent connection between said member and the casement; and a removable connection between the member and the casement adapted to secure said casement to said member.

3. In a casement, the combination of a frame; a sash; slotted arms pivoted to said frame; pins on said sash received in the slots of said arms; and bolts in said sash so disposed as to be received in the slots in said arms.

4. In a casement, the combination of a frame; a sash; slotted arms pivoted to said frame; pins on said sash received in the slots of said arms; sockets in said frame; and bolts in said sash so disposed as to be alternatively received in said sockets and in the slots in said arms.

5. In combination with a frame therefor of a casement; and means associated with said casement and frame, comprising manually operated inter-locking members, adapted when unlocked to permit said casement to be swung relative to said frame pivoting at the bottom of said frame, and when locked to permit said casement to be swung rela-

tive to said frame pivoting at the top of said frame.

6. A casement provided with means for limiting its movement when it is pivoted on its lower edge, and also provided with means adapted to secure said casement against longitudinal movement relative to said limiting means when the casement is pivoted at a point adjacent its upper edge.

In testimony whereof I affix my signature.

ALDEN A. POTTER.
